United States Patent Office

Des. 209,418
Patented Nov. 28, 1967

209,418

GRILLE OR SIMILAR ARTICLE

Norman Cutler, 400 Salisbury Road,
Wyncote, Pa. 19095

Filed Jan. 27, 1967, Ser. No. 5,582

Term of patent 14 years

(Cl. D54—2)

FIG. 1

FIGURE 1 is a front elevational view of a grille, or similar article, embodying my new design. The portion shown within the broken lines represents the basic design unit which is repeated. The back is the same.

The end and bottom not shown are the same as the respective end and top portions shown.

I claim:

The ornamental design for a grille or similar article, as shown and described.
